UNITED STATES PATENT OFFICE.

ARTHUR C. EASTWOOD, OF CLEVELAND, OHIO.

SYSTEM FOR ELECTRIC RAILWAYS.

No. 884,645.

Specification of Letters Patent.

Patented April 14, 1908.

Application filed February 2, 1907. Serial No. 355,396.

To all whom it may concern:

Be it known that I, ARTHUR C. EASTWOOD, a citizen of the United States, residing at Cleveland, in the county of Cuyahoga and State of Ohio, have invented or discovered new and useful Improvements in Systems for Electric Railways, of which the following is a specification.

My invention relates to certain new and useful improvements in electric railways with particular reference to the means for generating electric power and supplying it to any number of motors on a train.

The objects of my invention are to produce an electric railway which may be operated without the use of large central power plants and without the necessity of installing an expensive system of transmission conductors; wherein current may be generated and supplied to the motors at a relatively low voltage, thus insuring safety and freedom from insulation troubles which are naturally present where high voltages are employed; wherein the power generating apparatus, when working, will be operating at maximum efficiency; wherein the energy delivered in descending grades and in braking may be stored for future use instead of being wasted in the form of heat, as is generally the case at present; wherein the power generating apparatus may readily be placed at the rear of the train, thus adding to the comfort of passengers by eliminating the smoke and cinders, which are so objectionable where a steam boiler is carried at the forward end of the train; wherein standard railway cars, such as are at present in use, may be placed between the motor cars in a train without the necessity of providing such cars with control conductors or power cables and eliminating flexible couplings or plug connectors between cars; and which may be equipped at minimum expense and will possess a maximum of flexibility.

For the operation of trunk lines it has been proposed to erect large power plants at intervals along the railway and to generate and transmit electric current at a relatively high voltage, current being supplied to the motors through the medium of a stationary conductor fed by the power plant. The greatest objections to this system of generating and distributing power are as follows: A very heavy investment in power plants is required. If losses of power in transmission are to be kept within reasonable limits, the investment in the transmission system must also

be very heavy. To secure reasonable efficiency in transmission very high voltages must be employed, thus introducing elements of danger and risk of breakdown. Since each power plant must be of sufficient capacity to supply all trains which may at one time be operating on the section of road supplied by it, the various power plants for a considerable portion of the time may operate at very low output and at low efficiency on roads where trains run at infrequent intervals. If a single power plant or a section of the transmission system breaks down, an entire section of the road is rendered inoperative.

By means of my invention, all of the above objections are obviated. The investment in power generating apparatus need be only sufficient to meet the total demands of the road, and the power generating units will be worked at maximum efficiency. The maximum distance to which electric power must be transmitted to a given train will be the length of the train, so that no elaborate and expensive power transmission system is required and a relatively low and safe voltage may be economically employed. Further, the disabling of a single power generating unit can effect the operation of only a single train.

In carrying out my invention, I provide each train with its own electric power-generating plant, which travels with the train and is preferably located at the rear thereof. I provide a number of cars in the train with electric driving motors and supply them with power from the power plant on the train, the speed, power, and direction of rotation of all the motors being simultaneously controllable from a single point, preferably the forward end of the train. I preferably supply current from the power plant to the various motors on the train through the rails of the road and a third conducting rail or trolley wire. Of course, each car on the train could be equipped with a power conductor with the necessary detachable plug connections or couplings between the cars, thus forming a power conductor extending throughout the length of the train. I prefer, however, to use a stationary conductor, since with this construction, ordinary cars, such as might be used by roads not equipped with electric power, could be placed between the various motor-driven cars without addition or alteration.

I prefer to provide a storage battery on

the train which acts in parallel with the electric generator, such that, when a small amount of power is required to drive the train, surplus energy will be stored in the battery and when more than average power is required the battery will discharge and assist the generator. The battery may also be used in absorbing the energy which must be given up when the speed of the train is reduced, the motors being temporarily connected as generators for the purpose of braking.

Where there are extended grades on the road and the travel is approximately equally divided up and down grade, I instal stationary storage batteries, the batteries being connected between the rails and the stationary power conductor. Trains descending the grade will store energy in the stationary battery and this energy will be given up in assisting other trains in ascending the grade. Where travel is unequally divided, the bulk of the traffic being up-grade, I instal a stationary power generating plant delivering current at the point of grade, this plant acting in parallel with the plant on the train and furnishing the excess power required to drive the train up the grade. By these arrangements, I am enabled to work the power generating apparatus on the train at substantially constant load and at high efficiency.

Referring to the accompanying drawings, Figure 1 is a side elevation of a train equipped in accordance with my invention. Fig. 2 is a plan view partly in section, and Fig. 3, a side elevation, partly in vertical section, of one form of traveling power plant which I may employ. Figs. 4 and 5 are diagrams of electrical control connections. Fig. 6 is a plan; and Fig. 7, an elevation of a section of a roadway. Fig. 8 is a sectional view of the railway at a point where the control and power conductors overlap, together with an elevation of a car truck and contact shoes for the said conductors. Fig. 9 is a side elevation showing a portion of a railway with a power conductor and a contact shoe.

In Fig. 1, which represents a train of cars equipped in accordance with my invention, the cars, P^1 , P^2 , P^3 , and P^4 , are each equipped with electric driving motors which are controlled from the leading car P^1 . At the rear of the train and coupled thereto is a traveling power plant consisting of a boiler D , supplied with water and fuel from a tender d ; a steam engine E , preferably of the rotary or turbine type; an electric generator F ; and a storage battery B^a . The generator F is preferably of the unipolar type, which may readily be operated at high speed, generating direct current, no commutator being required. The engine E , generator F and battery B^a are preferably carried on a car P^1 , separable from the boiler, steam being transmitted from the boiler to the en-

gine through a detachable connection e ; or they may be carried on the same truck or platform or on the trucks which carry the boiler, but readily separable therefrom. I prefer this construction from the fact that the engine and generator, being of the rotary type, may be operated for long periods without repair, while the boiler and firebox, being of necessity worked at high output, must be frequently put into the shop for necessary inspection, cleaning, etc. In equipping a road, an excess of boilers may be provided so that the engine generators and batteries, which constitute the more expensive parts of the equipment, may be kept in almost constant operation. The battery B^a is so connected as to "float" in the system, storing energy or giving out energy according as the load on the generator F fluctuates.

I preferably supply current from the generator F and the battery B^a to the motors on the various cars, P^1 , P^2 , P^3 , etc. through the agency of the stationary conductor N (Fig. 6) placed parallel with the roadway. Contacts, (Figs. 8 and 9) are carried by the cars which have been equipped with motors, these contacts co-operating with the conductor N . The conductor N is divided into sections n as shown in Fig. 6, these sections being of such length that two trains will not be operated upon the same section at the same time. The sections n of the conductor overlap at their ends by a distance equal to the length of the longest train to be operated, so that a train may pass from one section to the next without interruption of the circuit, but the same object may be otherwise accomplished.

Referring to Figs. 8 and 9, it will be noted that the overlapping sections n of the power conductor N are arranged to be engaged by the two contact shoes n^2 carried by the links n^4 . The links have each a slot n^6 at its upper end to receive the guide bolt n^5 secured to the bracket or support n^7 on the car. n^8 is a shunt of flexible or braided copper wire which transmits the current collected by the shoe directly to the bracket n^7 , thereby relieving the joints of the links from carrying current. The ends of the sections n curve down as shown on Fig. 9.

The current from the generator, which is on one car, travels along the sections of the conductors, but it can not pass from one section to another unless the shoes n^2 are in contact with two sections simultaneously, the shoes being electrically connected. The current would not be delivered to any motor car which does not have its motor in circuit with the conductor section to which the generator is delivering its current. Therefore, the overlapping sections should at least be as long as the distance between the generator car and the most distant motor car in a train.

The conductor N, being required to transmit merely the current for one train through a mean distance of approximately half the length of the train, may be of relatively light section. The rails G form the return conductor of the circuit.

Referring now to Fig. 4, K is the controlling switch preferably carried by the leading car P¹ of the train, and is represented as of 10 the "drum" or cylinder type, there being a row of relatively stationary contact fingers b, b¹, b², b³, — b¹⁵, coöperating with a series of contact strips or segmental rings k¹ to k⁸, carried by the rotatable drum or cylinder. 15 The strips k¹ to k⁸ are all connected in a stepped series, each successive strip below the strip k¹ extending farther from the fingers than the one above it. These strips are short and are in contact with their respective 20 fingers only during the time the controller is at a corresponding speed position. The successive strips k²—k⁸ slightly overlap so that contact of a strip with its coöperating finger will be made before contact of the adjacent strip 25 with its finger is broken.

To furnish energy for actuating the motor-controlling devices, which are carried by the motor-cars of the train, I have provided the storage battery B divided into the sections 30 B¹—B⁸. These sections are connected to the contact-fingers b¹—b¹⁵ of the controller K as follows: The section B¹ is connected to the contact-finger b¹ by the wire a¹; the section B², to the contact-fingers b² and b³ 35 by the wire a²; the section B³, to the contact fingers b⁴ and b⁵ by the wire a³, and so on, the last section, B⁸ being connected to the contact-fingers b¹⁴ and b¹⁵ by the wire a⁸. The wires a²—a⁸ fork, the upper 40 branches leading through resistances r¹—r⁷, respectively, to the upper member of each pair of contact-fingers and the lower branch shunting the corresponding resistance and leading to the lower member of each pair of 45 contact-fingers.

The forward end of each contact-strip k²—k⁸ is notched, the upper portion thereof being wide enough to cover the upper member of the corresponding pair of contact-fingers, while the rear portion of each strip extends down far enough to cover the remaining member of the pair of contact-fingers. It will be readily seen that, when the contact-strip k² 50 engages the contact-finger b², the corresponding resistance r¹ will be included in the circuit which starts from the left side of the battery section B² and includes the wire a¹, the contact-finger b¹, the contact-strip k¹, the connection between this strip and the strip k², 55 the contact-finger b², the resistance r¹ and the wire a² to the right end of the said battery section. As the drum of the controller K is further advanced, the contact-finger b³ comes 60 into contact with the lower step of the strip k² just after the strip k¹ has left contact with

the finger b¹. The resistance r¹ is then short-circuited and the wire a¹ cut out of the circuit just traced. The succeeding strips and fingers are arranged in the same manner, the resistances r², r³, etc. in each case being short-circuited and the next preceding battery wire 70 a², a³, etc. being cut out of the battery circuit just after the pair of preceding contact-fingers has left the corresponding strips k², k³, etc.

As the drum of the controller is revolved 75 from the off-position, current from the successive sections of the battery B will be supplied through the control conductor M and the rails G to the controlling devices on the cars P¹, P², P³, etc. of the train, the step-by-step rotation of the drum of the controller K causing a progressively larger number of battery cells to be connected between the conductor M and the rails G.

W is a reversing switch preferably of the 80 form described in my pending application for United States patent, Serial No. 312,613. It will be seen that the operation of the reversing switch W, which, by a quarter revolution, moves the conductor strips w¹ and w², so that the strip w¹ will connect the contacts 85 1 and 2 and the strip w² will connect the contacts 3 and 4, will reverse the connections of the battery to the rail G and the control-conductor M, thus reversing the direction of current flow through the actuating devices of the 90 motor controllers on cars P¹, P², P³, and P⁴.

The control circuits on each of the motor driven cars P¹ to P⁴ are designated, respectively, by the characters p¹ to p⁴. It is to be 100 noted that one end of the control-circuit on each car is connected to the rail G, preferably through the truck of the car, and the other end of the control-circuit on each car is connected to contact shoes m² which coöperate 105 with the control-conductor M, which is made sectional like the power conductor N, the shoes m² being like the shoes n².

The arrangement of the circuits on each motor driven car is more clearly shown in 110 Fig. 5, in which A is the armature and F the field winding of a single driving motor. U is a reversing switch for reversing the direction of the motor, the terminals 5 and 8 being connected to the brushes of the armature; the 115 terminal 6, to one terminal of the resistance R, and the terminal 7, to one terminal of the field F. The remaining terminal of the field F is connected to the shoe n² which is in sliding contact with the conductor-rail N, whose 120 function is to conduct to the car-motors the propulsion current generated by the generator F, one terminal of the generator being connected to the conductor N and the other to the rails G.

The resistance R is divided into sections R¹, R²—R⁷ governed by the devices which control the speed and power of the motor. The sections of resistance are indicated as 125 controlled by magnetically operated switches 130

S^1, S^2, S^3 , the closure of each switch serving to short-circuit a section of the resistance connected to its terminals in the well known way. As shewn, the terminals of the sections of the resistance are connected respectively to one of the contacts of the several switches S^1, S^2 , etc. while the second contact of each of the said switches is connected to a common wire J , leading to the rail G . The switches may be of any type, the one shown being merely diagrammatic or intended to show the presence of automatic magnetically operated switches. The pair of contacts of the switches are closed by the action of the windings C^1, C^2 , etc. on their plunger-like cores having at their bottoms the bars s , which bridge the members of the several pairs of contacts when the windings energize the cores so as to lift the said bars into engagement with the said contacts. The windings of said switches are in series between the conductors leading to the rail G and the shoe m^2 on the control-conductor M . The plungers of the switches are shown as provided with successively heavier weights or bars so that a step-by-step increase in voltage between the rail G and the control-conductor M , which is obtained by rotating the drum of the controller K , will cause the successive closure of the switches S^1, S^2, S^3 , etc., thus increasing the speed of the motor because the closure of each switch cuts out a section of the resistance R .

The reversing switch U is indicated as operated in one direction or the other by electro-magnets having windings u^1 and u^2 .

u^3 is the winding of a polarized relay which controls the circuits of the windings u^1 and u^2 . When the polarized armature u^4 of the relay is on the contact u^5 , as shown, the coil u^1 of the reversing switch is energized, it being in series through the armature u^4 with the conductors leading to the rail G and the shoe m^2 . When, however, the direction of the current-flow through the coil u^3 of the relay is reversed (this being caused by operation of the reversing switch W of the controller K), the armature u^4 of the relay is attracted, opening the circuit of coil u^1 , and closing the circuit of coil u^2 , thereby actuating the reversing switch U and causing the armature A to rotate in the reverse direction. The energization of the winding u^3 moves the blade w^3 so as to bridge the contacts 5 and 6, and the blade w^4 so as to connect the contacts 7 and 8.

It will be readily understood that when the controller K on the leading car is operated so as to bring the strips on the drum successively into contact with their respective fingers b^1, b^2, b^3 , etc., the controlling switches S^1, S^2, S^3 , etc. on each of the cars P^1, P^2, P^3 and P^4 are operated; when the controller K is returned to the original "off-position", the circuits of the motors on each of the cars is

opened; and when the reversing switch W is again shifted and controller K is again operated, the motors will be started in the reverse direction and their speed and power will be controlled as before. My invention, therefore, affords very simple means for controlling the speed, power and direction of rotation of a plurality of motors on various cars of a train from a single point.

For the sake of simplicity I have shown a storage battery B as a source of power for actuating the control devices on the various cars of the train. Of course, other devices such, for example, as a motor generator, might be employed for the purpose, the requirements being that a variable voltage be available and that each step of the controlling switch K corresponds to a certain definite voltage between the control-conductor M and the rails G . Further, I have indicated but a single motor for each of the cars P^1 to P^4 . Of course, a number of motors might be applied to each car and the speed and power of these motors might be varied by altering the grouping of their windings; or, if the motors be of the alternating current type, the resistance R might be replaced by a controllable transformer or reactance. While I have shown the switches S^1, S^2, S^3 , etc. as operated by power furnished by the battery B , it is evident that the switches might be operated by compressed air or other power controlled by relays, the relays in turn being under the control of the switch K in a manner the equivalent of that shown and described.

The operation of my invention may be explained as follows:—The operator in the car P^1 turns the handle of the controller K so as to cause the strips k and k^1 to contact with the fingers b, b^1 , whereupon current from the section B^1 of the battery B flows through contacts 1 and 3 of the reversing switch W to the rail G . Leaving the rail G as indicated in Fig. 5, the current divides; one portion passes from the rail G through the winding u^3 of the polarized relay, and thence to the contact shoe m^2 and returns through the control-conductor M and the contacts 2 and 4 of the switch W to the terminal of the battery B . This completes the circuit through the coil u^3 of the polarized relay, and assuming that the current flows in such a direction as to repel the armature u^4 so that it makes contact with the terminal u^5 , as shown, a second circuit is established from the rail G through the armature u^4 of the relay, the contact u^5 , the coil u^1 of the reversing switch U , thence to the contact shoe m^2 , and through the control-conductor M to the battery. This energizes the actuating coil u^1 of the reversing switch, which we will assume causes the contact strip w^3 to bridge the contacts 5 and 7 and the contact strip w^4 to bridge the contacts 6 and 8. Current from the control battery also passes from the rail G through the

switch coils C^1 to C^8 in series. The switch S^1 having a plunger of lighter weight than the others closes first, and establishes the main circuit through the motor as follows:

- 5 From the power-conductor N through the contact shoe n^2 , the motor field winding F , the contacts 7 and 5 of the reversing switch U , the motor armature A , the contacts 8 and 6 of the reversing switch U , the entire resistance R^7 to R^1 , and thence through the contacts of the switch S^1 to the rails G , through which the current returns to the traveling power plant.

When the controller K has been rotated 15 so as to bring the strip k^2 in contact with the fingers b^2 and b^3 , the battery section b^2 will be placed in series with the section B^1 . As the controller is further rotated to bring the successive strips in contact with their respective fingers, the successive sections of the battery will be connected in series with those already in circuit. This causes successive closure of the magnetic switches S^2 , S^3 , etc., which short-circuit the controlling 20 resistance in an obvious manner until, when switch S^8 closes, all of the resistance is short-circuited and the motor should operate at full speed.

To reverse the direction of motion of the 30 motors, the operator throws the reversing switch W , Fig. 4, so that contacts 1 and 2 are connected together, and contacts 3 and 4 are connected together. When the controller K is then operated in such a manner that

35 the strips k , k^1 are in contact with the fingers b , b^1 , current will pass from the first section B^1 of the battery B through contacts 1 and 2 of the reversing switch W , thence to the control conductor M , and through all of the 40 switch-actuating coils and through the winding of the polarized relay in a reverse direction from that previously described, since the polarity existing between the control-conductor M and the rails G has been reversed.

45 This reversal of the direction of current flow will cause the polarized relay to attract its armature u^4 bringing it into contact with the terminal u^6 which is in connection with the actuating coil u^2 of the reversing switch.

50 This completes the circuit through the coil u^2 and causes the contact strip w^3 to bridge the contacts 5 and 6 and the contact strip w^4 to bridge the contacts 7 and 8. The switches S^1 to S^8 will act the same as before, since 55 their action depends merely upon the amount of current flowing through their windings and not upon its direction. Switch S^1 will, therefore, close as before and establish the main circuit through the motor as follows:

60 Current will flow from the power-conductor N through the contact shoes n^2 , the field F , the contacts 7 and 8 of the reversing switch, the armature A , contacts 5 and 6 of the reversing switch U to the control resistance, 65 thence through all of the resistances R^7 to

R^1 , and through the contacts of the switch S^1 to the rails G , thence returning to the power-house. It will be noted that the direction of current flow through the armature A has been reversed while current flows 70 through the field F in the same direction as before. The direction of rotation of the motor will, therefore, be reversed. Further actuation of the operating controller K will cause successive closure of the switches S as 75 before, cutting out resistance R and increasing the speed.

By dividing the control-conductor M into sections, I prevent any interference with the motor-controlling devices of one train by another train. The potential between the rails G and M determines the number of the switches S^1 , S^2 , etc. thrown in and, therefore, the speed of the train. Obviously if the control-conductor were continuous along the 80 railway and a number of trains were on the railway at the same time, the motorman of each train might have his operating controller K on a different point, so that the control-batteries B on the various trains 85 would tend to produce varying differences of potential between the control-conductor M and the rails G , according to the number of battery cells admitted into circuit by the various controllers. This would, of course, set 90 up cross-circuits between the control apparatus of the various trains and interfere with proper control.

Fig. 6 is a plan, and Fig. 7, an elevation of a section of double track railway. G , G are 100 one pair of rails and G' — G' , the rails of the parallel track. N and N' are the respective stationary power-conductors for the two tracks, and M , M' , the control-conductors. A grade is indicated at H . A battery T^1 is 105 located at or near the point of grade and is connected to the rails and power conductor in such manner that trains descending the grade may be caused to store energy in the battery by connecting the motors on the 110 train to act as generators.

A generator F' driven by a suitable prime mover such as a steam engine or water wheel delivers electric power at the point of grade and is adapted to coöperate with the generator on a train ascending the grade. The battery T' is also arranged to give up energy stored by trains descending the grade in assisting trains running in the opposite direction in mounting the grade. 115

It is to be understood that portions of my system may be modified while others remain unchanged, and that the details and combinations thereof may be variously constructed and arranged without sacrificing the characteristic features thereof, as specified in the claims. 120

I claim—

1. In a railway system, a train of cars, a source of electric current on one of said cars, 130

electric translating devices on certain of said cars, and a stationary conductor along said railway for connecting said translating devices with said source of current.

5 2. In a railway system, a source of electric current traveling on said railway, a train of cars, electric translating devices on certain of said cars, a stationary conductor along said railway and connected by a traveling 10 connection with said source of current and with the translating devices on said cars.

3. In a railway system, a train of cars, a source of electric current on one of said cars, electric translating devices on certain of said 15 cars, and a stationary sectional conductor along said railway for connecting said translating devices with said source of current.

4. In a railway system, a source of electric current traveling on said railway, a train of 20 cars, electric translating devices on certain of said cars, a stationary sectional conductor along said railway and connected by a traveling connection with said source of current and with the translating devices on said cars.

25 5. In a railway system, a train of cars, a source of electric power on said train, electric driving motors on certain of said cars, and a stationary power conductor along said railway, adapted to connect said electric 30 driving motors with said traveling source of power.

6. In a railway system, a train of cars, a source of electric power on said train, electric driving motors also on said train, and a 35 sectional stationary power conductor along said railway, adapted to connect said electric driving motors with said traveling source of power.

7. In a railway system, rails, a train of 40 cars thereon, a source of electric power on said train, electric driving motors on certain of said cars, a stationary power conductor along said railway, and traveling contacts carried by said train whereby the said driving 45 motors may be connected to said source of power through said stationary power conductor and the rails of said railway.

8. In a railway system, a train of cars, a source of electric power on said train, electric 50 driving motors on certain of said cars, a stationary power conductor along said railway for connecting said motors with said source of power, said power conductor being divided into insulated sections, and means for 55 maintaining the connection between said driving motors and said source of power when the train is passing from one insulated section to another.

9. In a railway system, rails, a train of cars 60 thereon, a traveling source of electric power, electric motors and controlling devices therefor on certain of the cars of said train, and a stationary power conductor along said railway, which, together with the rails of said 65 railway, is adapted to connect said motors

through their controlling devices to said traveling source of power.

10. In a railway system, a train of cars, a traveling source of electric power, electric motors and controlling devices on certain of 70 said cars, a master-switch on one of said cars for causing the actuation of said controlling devices, a stationary conductor along said railway for connecting said motors through said controlling devices to said traveling 75 source of power, and a second conductor along said railway for connecting said master-switch to the operating mechanism of said controlling devices.

11. In a railway system, a train of cars, a 80 traveling source of power, electric motors on certain of said cars, means for connecting said motors to said traveling source of power, and means for controlling said motors in unison from a single point, said connecting 85 means and said controlling means being independent of the cars not equipped with electric motors.

12. In a railway system, a train of cars, a source of electric power on said train, electric 90 motors on certain of the cars of said train, and means independent of the cars not equipped with electric motors for connecting said motors to said source of power and for controlling the speed of said motors. 95

13. In a railway system, a train of cars, a source of electric power on said train, electric motors on certain of the cars of said train, and means independent of the cars not equipped with electric motors for connecting 100 said motors to said source of power and for controlling the speed and direction of motion of said motors.

14. In an electric railway system, a stationary power conductor adjacent to the 105 railway, a traveling electric power plant adapted to said railway, and a traveling connection between the power conductor and the power plant for energizing the former.

15. In an electric railway system, a stationary power conductor adjacent to the railway, a traveling electric power plant adapted to said railway, and a traveling connection between the said power conductor and power plant for energizing the former, said power 115 conductor being composed of insulating sections with their ends overlapping.

16. In an electric railway system, a stationary power conductor adjacent to the railway, a traveling electric power plant 120 adapted to said railway, and a traveling connection between the said power conductor and power plant for energizing the latter, said power conductor being composed of insulated sections with their ends overlapping 125 a distance equal to the greatest length of trains to be operated on said railway.

17. In an electric railway system, a power conductor adjacent to the railway, and a stationary source of power and a source of 130

power adapted to travel on said railway for energizing said power conductor.

18. In an electric railway system, a sectional power conductor adjacent thereto, a traveling power plant for consecutively energizing the sections of said power conductor, and a stationary source of power for supplying additional energy through certain of the sections of said power conductor.
19. A power distribution system for electric railways, embracing a stationary power conductor adjacent to the railway, and a power plant movable along said railway and adapted to create a difference of potential between said stationary power conductor and the rails of said railway.

20. A power distributing system for electric railways, embracing a stationary source of electric energy, means for storing electrical energy, a source of electric energy 20 movable on said railway in combination with a stationary power conductor divided into insulated sections, and means for connecting said sections to the several sources of energy.

Signed at State, county and city of New York, this 31st day of January, A. D. 1907.

ARTHUR C. EASTWOOD.
